UNITED STATES PATENT OFFICE.

WALTER A. CROWDUS, OF CHICAGO, ILLINOIS.

DESIGN FOR AN AXLE-SUPPORT FOR VEHICLE-FRAMES.

SPECIFICATION forming part of Design No. 34,828, dated July 23, 1901.

Application filed June 25, 1901. Serial No. 66,017. Term of patent 14 years.

To all whom it may concern:

Be it known that I, WALTER A. CROWDUS, a citizen of the United States, and a resident of Chicago, in the county of Cook and State 5 of Illinois, have invented and produced a new and original Design for an Axle-Support of a Vehicle-Frame, of which the following is a specification.

In the accompanying drawings, Figure 1 is 10 a side view of an axle-support of my design, and Fig. 2 is a top plan view thereof.

An axle-support of my design comprises, essentially, a member A, which is upwardly bowed between its ends, upward projections 15 A', and downwardly-extending arms A², lo-

cated adjacent to the middle of said axle-support.

I claim—

The design for an axle-support of a vehicle-frame, substantially as herein shown and described. 20

In testimony that I claim the foregoing as my invention I affix my signature, in presence of two subscribing witnesses, this 25th day of May, A. D. 1901.

WALTER A. CROWDUS.
